UNITED STATES PATENT OFFICE.

JOHN EDWARD OGDEN, OF MOUNTAINVILLE, NEW YORK.

EXPANSION SHIELD.

Application filed October 21, 1921. Serial No. 509,360.

To all whom it may concern:

Be it known that I, JOHN EDWARD OGDEN, a citizen of the United States, and a resident of Mountainville, town of Cornwall, 5 Orange County, and State of New York, have invented certain new and useful Improvements in Expansion Shields, of which the following is a specification.

This invention relates to bolt anchors and 10 more particularly to expansion shields for bolt anchors and to the manufacture of such devices.

One of the objects of the invention is to provide a simple and inexpensive device of 15 the character described which may be effectively used to hold a bolt or screw in material such as stone, brick or cementitious material with which the threaded element can not directly obtain a secure hold.

20 Another object of the invention is to provide an expansion shield which may be readily manufactured.

Another object of the invention is to provide a simple and inexpensive method for 25 manufacturing expansion shields.

Further objects of the invention will appear from the following specification taken in connection with the drawings which form a part of this application and in which,

30 Fig. 1 is an elevation of an expansion shield constructed in accordance with my invention.

Fig. 2 is an elevation of one of the sections of the expansion shield shown in 35 Fig. 1.

Fig. 3 is an end elevation of the outer end of the shield shown in Fig. 1.

Figs. 4, 5 and 6 are transverse sectional views taken substantially on lines 4—4, 5—5 40 and 6—6 of Fig. 1.

Fig. 7 is an end elevation of the inner end of the shield shown in Fig. 1.

Fig. 8 is a sectional elevation of a shield similar to that shown in Fig. 1 but in which 45 the shield sections are secured together by lugs carried by each section.

Fig. 9 is a plan view of the blank from which one of the shield sections is formed.

Fig. 10 is a similar view of the other 50 shield section blank, and

Fig. 11 is a plan view of a modified form of blank from which the shield shown in transverse section in Fig. 8 may be formed.

The invention may be briefly described as 55 a shield comprising a plurality of sections folded transversely and secured together to

form a tube having opposite parts depressed or tapered to constrict the bore of the tube toward the inner end. The metal at the edges of the shield sections is folded in such 60 a manner as to provide an excess of metal at the outer surface of the constricted portion of the tube. In the particular embodiment of the invention shown the cross section of the tube varies from a circle at the outer end 65 to a flattened curve or oval at the inner end. Also as particularly illustrated the folds do not extend throughout the entire length of the shield and are double for a portion of 70 their length and are single for another portion of their length. Further and more detailed features of the invention will be explained in the description of the particular structure shown in the drawings.

Like characters of reference designate corresponding parts throughout the several views of the drawings.

Referring first to Figs. 9 and 10 the shield may be formed from a pair of blanks 20 and 21 adapted to be secured together by lugs 22 shown as formed on the blank 20. The blank 21 is illustrated as having depressed portions 23 for receiving the lugs 22. If desired, however, each blank, as shown in Fig. 11, may have a lug 22' and a depression 23' instead of both lugs being formed on one blank and both depressions being formed in the other blank.

Each blank has also formed thereon for a short portion of its length adjacent the outer end an outwardly projecting rib 24 formed by crimping the metal at this point. These ribs in the completed shield assist in preventing the rotation of the shield in the opening in which the shield is positioned when the threaded member is being inserted in the shield. For a portion of its length at the outer end each blank has substantially parallel edges 25. The edges beyond the parallel portions 25 are tapered as shown at 26 to provide an excess of metal as hereinafter described and the end portions of the blanks are also tapered as shown at 27, this portion 27 constituting the outer portion when the blank has been folded transversely and the two complementary blanks have been combined to form the shield. It will be noted that the mean width of the tapered portion 26 of the blank 100 is less than the mean width of the tapered portion 27 and that the outer edges of the tapered portions 27 are inclined with re-

spect to the longitudinal axis of the blank at the same angle as are the edges of the tapered portions 26. In other words, the edges of the portions 27 if extended would 5 be parallel to the edges of the portions 26.

The blanks 20 and 21 are corrugated as shown at 28 and 29, transversely of the blanks, and these corrugations of the two blanks are complementary so that, when 10 the blanks are folded and combined, they form the threads for receiving the bolt or threaded member which is inserted in the shield.

The blanks shown in Figs. 9 and 10 are 15 folded transversely about longitudinal axes and are secured together forming the shields in Fig. 1. As the blanks are folded, the substantially parallel portions 25 of the side edges are slightly flanged or turned outwardly as shown at 30 and the tube formed by the joined sections is internally tapered as shown in Fig. 2 by depressing the metal of the opposite blanks. It will be noted that the form of the tubular shield changes 20 from substantially a circle at the outer end to a flattened curve or oval at the inner end, the two ends being shown respectively in Figs. 3 and 7.

The tapered portions 26 and 27 of the 30 blanks were designed to provide an excess of metal adjacent the flattened portions of the tube. This is accomplished by folding the tapered portions 26 and 27 outwardly on a plane disposed substantially at right 35 angles to the major axis of the flattened curve or oval portion of the bore or, in other words, these portions are folded outwardly along the lines forming continuations of the lines of division between the 40 shield sections. The portions 26 and 27 are then folded back toward or upon the outer flattened surfaces of the sections and the portions 27 are again folded back upon themselves until their edges meet. The portions 45 26 therefore form single folds on the outer surfaces of the shield sections and the portions 27 form double folds. By reason of the tapering form of the edge portions 26 and 27, the folds are tapered 50 longitudinally and, as shown in Fig. 2, the portions 27, when folded, form tapered longitudinal chambers. By means of these folds on the outer constricted portions of the shield the substantially cylindrical form 55 of the shield is maintained throughout its length. It will be understood of course, that as the threaded element is inserted in the shield the constricted portion is forced outwardly by this element and the excess of 60 metal formed by the folds is pressed into firm engagement with the wall of the opening in which the shield is positioned.

From the above description it will be 65 seen that a simple and practical expansion shield has been designed and that this shield

may be readily manufactured. Furthermore the shield is so constructed that in use it will firmly and securely engage the opening in which it is positioned.

Although one specific embodiment of the 70 invention has been illustrated and described it will be understood that the invention is capable of modification and that changes in the construction and in the arrangement of the various cooperating parts may be made 75 without departing from the spirit or scope of the invention as expressed in the following claims.

What I claim is:—

1. An expansion shield comprising a tubular member formed from a plurality of sections and having a bore tapered toward the inner end and having oppositely tapering longitudinally extending folds on its outer surface, formed by folding the metal, 80 at the longitudinal edges of the sections, back upon itself, the folds at the inner, more constricted portion of the shield being double and at the less constricted portion 85 being single.

2. An expansion shield comprising a plurality of sections secured together to form a tubular member, the metal at the edges of the sections being folded back upon itself 90 to provide an excess of metal on the outer surface, the folds adjacent the inner end of the shield being double and toward the other end being single.

3. An expansion shield comprising a plurality of sections secured together to form 100 a tubular shield, the metal at the edges of said sections being bent outwardly for a portion of the length of the shield, being bent over the outer surface of the sections 105 for another longitudinal portion and being doubled back over itself for a third portion.

4. An expansion shield comprising a plurality of sections constricted toward one end and secured together to form a tapered 110 tubular shield, the metal at the edges of said sections being bent outwardly for a portion of the length of the shield, being bent over the outer surface of the sections for another longitudinal portion and being doubled back over itself for a third portion.

5. An expansion shield comprising a plurality of sections constricted toward one end and secured together to form a tapered, tubular shield, the metal at the edges of 115 said sections being bent outwardly for a portion of the length of the shield, being bent over the outer surface of the sections for another longitudinal portion and being doubled back over itself until the edges 120 meet for a third portion.

6. A sheet metal expansion shield having more metal at one end than at the other, comprising a plurality of sections folded transversely and secured together to form 125 a tube with the outer portions of greatest

- diameter lying in substantially the same cylinder, and with opposite parts increasingly depressed to form a bore varying from a substantially circular cross section 5 to a flattened curve, and with parts adjacent to the depressions folded back on the outer surface of the shield and doubled back on itself to form three thicknesses of metal at the more constricted portion of the bore.
- 10 7. A sheet metal expansion shield comprising a tubular body formed from a plurality of sections secured together, and having a tapered opening, each of the sections having at each longitudinal edge longitudinal folds of a double thickness of metal 15 adapted to be pressed into the walls of an opening when the shield is expanded therein.
8. A sheet metal blank for an expansion shield having substantially parallel side edges for a portion of its length, having its side edges flared for another portion of its length and having a second flared portion of greater width than the maximum width 20 of the first flared portion, for a third portion of the length of the shield.
9. A sheet metal blank for an expansion shield having substantially parallel side edges for a portion of its length, having its side edges flared for another portion of its length and having a second flared portion for a third portion of its length, the mean width of the second flared portion being greater than the mean width of the first flared portion. 25
10. A sheet metal blank for an expansion shield having substantially parallel side edges for a portion of its length, having its side edges flared for another portion of its length and having a second flared portion, 30 the edges of the second flared portion being inclined at the same angle with respect to the longitudinal axis of the shield as the edges of the first flared portion. 35

In witness whereof, I have hereunto set 45
my hand this 19th day of October, 1921.

JOHN EDWARD OGDEN.
